UNITED STATES PATENT OFFICE.

GEORGE HENRY KEYSER, OF AKRON, OHIO.

MECHANICAL DIRECTORY.

1,373,966.

Specification of Letters Patent.

Patented Apr. 5, 1921.

Application filed January 2, 1920. Serial No. 348,745.

To all whom it may concern:

Be it known that I, GEORGE HENRY KEYSER, a citizen of the United States, residing at Akron, in the county of Summit and 5 State of Ohio, have invented new and useful Improvements in Mechanical Directories, of which the following is a specification.

This invention relates to a mechanically operated device designed to carry a list of 10 names, data or other information, any particular item of which will be presented automatically by the operation of the device.

The main object of the invention is to provide a device which will hold a long strip 15 of sheet material whereon have been printed or otherwise registered numerous items of information to which instant reference is frequently necessary or desirable so that any particular item thereon will be quickly and 20 automatically presented by mechanical means controlled by the operator.

Another object is to provide a device of the class above referred to which will mechanically present a space whereon can be 25 written or otherwise registered items in alphabetical or class order so that the device may be operated to present any one of the items, instantly, as desired.

A still further object is to provide a device 30 of the class above set forth which is of simple, durable construction, which can be manufactured at a low cost and which will be accurate and economical in operation.

The above and other objects are attained 35 by the novel construction, combination and arrangement of parts hereinafter described and illustrated in the accompanying drawings which form a part hereof and wherein is shown a preferred embodiment of the in- 40 vention, it being understood that changes, variations, and modifications may be resort- ed to which come within the scope of the claims hereunto appended.

The nature and scope of my invention will 45 be more fully understood from the following description taken in connection with the accompanying drawings in which,

Figure 1 is a plan view of a device em- 50 bodying the main features of my invention, Fig. 2 is a plan view of the main working parts of the said device taken with the top removed,

Fig. 3 is a side elevation of same, having 55 portions broken away to more clearly illustrate the construction thereof,

Fig. 4 is a longitudinal sectional view of said device taken approximately on line 4—4 of Fig. 2.

Fig. 5 is a transverse sectional view taken on line 5, of Fig. 2. 60

Fig. 6 is a transverse sectional view of the means provided to support the strip of sheet material hereinafter described.

Fig. 7 is a diagram of the electric wiring employed in the construction of said device. 65

Fig. 8 is a view of the gear shifting mechanism employed.

Referring now to the drawings speci- 70 fically, in which like numerals of reference are employed to designate like parts throughout the several views, the numeral 1 is used to denote a box-like casing and the numeral 2, the lid of said casing. The numeral 3 indicates a glass covered opening in said lid adjacent one end of said casing. 75

The horizontal shaft 4 is pivotally mounted in the adjustable bearings 5 and 6, one of which is positioned in each side of said casing. Rigidly secured on the shaft 4, in a central position, is the spool 7. The driving sheave 80 8 is also rigidly secured on the shaft 4 ad- jacent one end thereof and in spaced relation to the end of the spool 7. The brake sheave 9 is rigidly fixed on the shaft 4 adjacent the other end thereof, in spaced relation to the 85 spool 7. Rotatably mounted in the bearings 10 and 11, which are similar to the parts 5 and 6 is the shaft 12 on which is rigidly se- cured the spool 13 which is similar to the 90 spool 7 and is positioned in alinement therewith. One end of the spool 13 is grooved around its periphery to provide the sheave 14. The brake sheave 15 is rigidly fixed on said shaft 12 in alinement with the sheave 9. Attached to the bottom of the casing 1 95 between the spools 13 and 7 is an electric motor 16 which has a drive shaft 17 on which is rigidly mounted a toothed collar 18. The outwardly extending end of the collar 18 is provided with teeth which are inclined, 100 and adapted to engage the teeth in the sheave 19 which is held against said collar 18 by the action of the spring 20 against the collar 21 on the extreme end of the shaft 17.

The teeth in both the collar 18 and the 105 sheave 19 are inclined so that the rotation of the shaft in a clockwise direction will rotate the sheave 19, but the rotation of the shaft 17 in a contra-clockwise direction will disengage the sheave 19 from the collar 18. 110

The sheave 22 is mounted on the said shaft 17 on the side of the collar 18 and is provided with teeth similar to the teeth in the sheave 19, so that the teeth in the collar 18 5 will engage the teeth in the sheave 22 when the shaft 17 is rotated in a contra-clockwise direction, and will likewise disengage therefrom when the shaft 17 is rotated in a clockwise direction. The sheave 22 is normally held 10 against the collar 18 by the spring 23 operating against the collar 24 which is attached to the shaft 17. The endless flexible member 26 is operatively mounted around the periphery of the sheaves 19 and 8 so that 15 the rotation of the sheave 19 will rotate the shaft 4 and the spool 7. The numeral 25 denotes an endless flexible member which is operatively mounted around the periphery of the sheave 22 and the sheave 14 so that 20 the rotation of the sheave 22 will cause the rotation of the shaft 12 and the spool 13.

Mounted in spaced relation transversely across the top of the casing 1 are the bars 28 and 29. The bar 28 is provided with a 25 pair of brackets 34 and 35 between which is mounted the member 32, which will be hereinafter more fully described. The roller 31 is rotatably mounted between the brackets 34 and 35 directly above and in approximate 30 contact with the member 32. The member 32 has a central portion 33 composed of rubber, wood or other non-conductor of electricity, while both ends of the member 32 are composed of copper, 35 brass or other electric conducting material. The brackets 34 and 35 are insulated from the bar 28 by a thin strip of insulating material 70. The bar 29 is provided with a roller 30 which is rotatably mounted 40 between the brackets 40 and 41, the axis of the roller being parallel to the axis of the spool 7. A roll of paper, celluloid or other flexible material 36 has one end fixed to and is wound about the core of the spool 7 and 45 passes over the roller 30 and between the member 32 and the roller 31, the other end of the flexible member 36 being fixed to and wound about the core of the spool 13. The lid is provided with a circular dial 37 on 50 which are printed or otherwise registered letters, figures or other characters indicating various positions on the flexible material 36. An indicating hand 38 is mounted on the vertical shaft 39 which projects through the 55 center of the dial 37, the said shaft 39 extending downwardly through the lid 2, the lower end thereof being provided with a beveled pinion 42 adapted to mesh with the pinions 43 and 44 which are mounted in 60 spaced relation on a horizontal shaft 45 which in turn is slidably journaled in the sides of the casing 1. The pinions 43 and 44 are positioned in said shaft so that the longitudinal movement thereof in one direction 65 will cause the pinion 43 to mesh with the

pinion 42 and a longitudinal movement of said shaft 45 in the other direction will cause the pinion 44 to mesh with the pinion 42. The shaft 45 is also provided with a ratchet-faced wheel 46, against which rests 70 a pawl 47 which in turn is pivotally secured on the horizontal shaft 50. Each end of the shaft 50 is journaled on suitable standards 48. The pawl 47 has a wide face so as to be in contact with the ratchet-face of 75 the wheel when the shaft is shifted longitudinally as hereinafter set forth. The pawl 47 is arranged to permit the rotation of the wheel 46 in only one direction. Rigidly secured to the shaft 50 is a horizontal 80 arm 49 carrying an actuating pawl 51 which is normally held in an upward position by the action of the spring 52 having one end attached to the pawl 47 and the other end to the pawl 51 adjacent the point where the 85 pawl 51 is pivoted to the arm 49. The other end of the shaft 50 is provided with an arm 54 which is rigidly attached thereto and extends horizontally, parallel to the arm 49. The outwardly extending end of the arm 54 90 is provided with a plate 55 which is normally held in the position shown in Fig. 4 by the spring 52. Directly beneath the plate 55 is an electromagnet 53 the face of which is near enough to the plate 55 to 95 cause a downward movement of said plate when the magnet is operated. A downward movement of the plate 55 will cause a rotary movement of the shaft 50 and the pawl 51 will be moved downwardly. The plate 55 100 being released from the influence of the magnet, the spring 52 will cause the pawl 51 to resume its normal position, thus causing a slight rotary movement of the wheel 46, the shaft 45 and the indicating hand 38. 105 One terminal of the magnet is connected to the negative pole of the battery or other source of electrical energy by the wire 58 as shown in the diagram set forth in Fig. 7, the other terminal of the magnet 53 being 110 connected by the wires 59 to the point 57 on one end of the member 32. The other end of the member 32 is connected at 56 by the wire 60 to the positive pole of the battery or other source of electrical energy. 115 The central portion 33 of the member 32 being composed of material which is a non-conductor of electricity, it will be seen that the magnet 53 will be operated by closing the gap formed by the insulating material 120 33. The long strip of sheet material 36 has secured to its inner surface a plurality of strips of tin-foil or other electric conducting material 62, these strips being adhesively secured or otherwise fixed to the strip 36 at 125 points indicated by the characters on the dial 37. The shaft 45 is further provided with a collar 67 which is rigidly fixed to the shaft in spaced relation to the hub 68, on the wheel 46. A lever 69 is pivotally 130

mounted on a pin 70 which runs at a right angle to the shaft 45 and is secured to the frame 73, directly beneath the space between the collar 67 and the hub 68. The said lever 69 is arranged to slide the shaft 45 longitudinally in either direction. Positioned on each side of said lever 69 are the electro-magnets 71 and 72. Both the magnets 71 and 72 are connected to a source of electrical energy as shown in Fig. 7. The switch 75, hereinafter described, is arranged to operate the magnet 71 when the motor is run in one direction, thus drawing the arm 69 against the operating face of the magnet 71 and shifting the shaft 45 so that the pinion 44 will engage the pinion 42 and cause the indicating hand 38, when actuated as hereinafter described, to move in a direction corresponding to the movement of the flexible member 36. Likewise when the switch 75 is operated to cause the motor 16 to wind the spool in the other direction, the magnet 72 will cause the lever 69 to shift the shaft 45 in the other direction causing the indicating hand 38, when actuated as hereinbefore described, to be given a movement corresponding to the movement of the flexible strip of sheet material 36.

Attached in spaced relation to the sides of the casing 1 are the inwardly extending flexible members 63 and 64 on which is fixed the rod 65 having a collar 66 to which is attached a vertical rod 74 which extends through the lid 2; the flexible members 63 and 64 being arranged to normally hold the rod 65 above the grooves in the sheaves 9 and 15.

Mounted on the support 77 on one side of the casing 1 is a lever-like member 76 the free end of which is provided with a laterally projecting portion adapted to contact with the periphery of the wheel 78 on the shaft 45. The lever 76 is fulcrumed on the support 77 at 80 and is held against the periphery of the wheel 78 by the spring 79. The peripheral portion of the wheel 78 is of triangular cross section, the lateral sides of the wheel converging to form a knife-like circumferential edge, so that the shaft 45, when shifted in either direction, will be held in that position against unintentional movement.

The motor 16 is of the reversible type and is connected to a reversible switch 75 which is operated by the crank 81 so that when the crank 81 is in the position shown in Fig. 1, the current is not admitted to the motor, but the shifting of the crank 81 at the point F will connect the motor to the source of electrical energy and operate it in a forward direction, simultaneously shifting the shaft 45 to cause the indicating hand 38 to move in a clockwise direction, likewise the movement of the crank 81 to the point R, as shown by the dotted lines in Fig. 1, will

reverse the motor 16 and simultaneously connect the electro-magnet 72 with the source of electrical energy thus moving the lever 69 against the operating face of the magnet 72 and shifting the shaft to a position shown in Fig. 8, thus engaging the pinion 43 with the pinion 42 so that the rotation of the shaft 45 by the action of the electromagnets 53 will operate the indicating hand 38 in a contra-clockwise direction.

While one method of wiring my device is shown in Fig. 7, it is to be understood that the device may be wired by other methods and other types of electrical apparatus may be used.

While a device embodying this invention is adapted to be used for a large number of purposes, for the purpose of illustration, I will describe it as being used as a telephone directory. On the strip of flexible material 36, there is printed or otherwise registered the names of telephone users and the number of each telephone. These names are printed in alphabetical order beginning with A at one end of the strip of sheet material 36 followed by the names beginning with B, this order being carried throughout the list of telephone users; on the reverse side of the strip 36 a sufficient number of electrical conducting strips 62 are secured to insure the movement of the indicating hand 38 when the strip has been unrolled so that, when the names beginning with the letter B are positioned between the roller 30 and 31, the strips 62 connect the two terminals of the electro-magnet 53 operating the hand 38 as hereinbefore described. The strips 62 are secured to the strip of sheet material 36 so as to cause the hand 38 to

indicate the first letter of the list of names on the strip between the rolls 31 and 30.

The indicating hand 38 thus points to the letter corresponding with the first letter of the name of the telephone users as the name is positioned before the window 3. To illustrate, if the indicating hand 38 on the dial 37 is at A as shown in Fig. 1 and it is desired to ascertain the telephone number of the subscriber whose name begins with R,

the crank 81 is so moved to F which connects the motor with the source of power and will cause the strip to pass before the window 3, the hand 38 moving in a clockwise direction until it has reached the letter R, whereupon the operator turns the crank 81 to the position shown in Fig. 1 thus stopping the motor, at the same time pressing in the rod 74, which causes the rod 65 to engage the sheaves 9 and 15 and thus preventing the further rotation of the spools 13 and 7 by momentum. As the device is thus stopped, the names beginning with the letter R will be positioned beneath the window 3 so that the name and number desired will be quickly presented to the oper-

ator. If the operator then desires to ascertain the telephone number of another subscriber whose name begins with the letter D, the crank is turned to R, which operates 5 the motor in the opposite direction and causes the indicating hand to move in a contra-clockwise direction. When the hand has reached the point on the dial corresponding to the point desired on the flexible 10 strip, the crank 81 is turned to the position shown in Fig. 1 and the rod 74 is operated, thus stopping the rotation of the spools.

The device may also be used to record 15 names, accounts or other data, in alphabetical or class order, in which case the glass is removed from the opening 3 and the names written on the flexible strip. If, for illustration, an account is to be entered against a customer, the proper operation of the de- 20 vice will move the indicating hand to the first letter of the customer's name and a transaction may be entered on the flexible strip in the space presented below the window 3. In posting the account to another 25 book, much time will be saved as all the names will be registered thereon in alphabetical order.

While I have indicated the above ways in which the device may be used, I do not 30 limit myself to such usage, as the device is adapted to be used for various purposes, in a great many ways.

Having thus described my invention what I claim as new and desire to secure by Letters Patent is:—

1. In a device of the class described, a casing, a strip of flexible material positioned in said casing, a window in said casing, means to move said flexible material 40 longitudinally beneath said window, characters registered on said flexible material in class order, a dial on said casing, index characters corresponding to the class of the characters on the flexible material, registered on said dial, an indicating hand on said dial and means connected with the movement of said flexible material to automatically move said hand to points on said dial which indicate the class of characters 45 on said strip as the same is positioned beneath the window on said casing.

2. In a device of the class described, a suitable support, a pair of rollers mounted on said support, a strip of sheet material 55 wound around said spools and having one end thereof secured to the core of one of said spools and the other end secured to the core of the other spool, items registered on said sheet material in class order, means to 60 wind said sheet material from one spool to another, a dial on said support, said dial having characters registered thereon to indicate the classification of said items, an indicating hand on said dial, means con- 65 nected with the means to move said spools

whereby the indicating hand is automatically moved to the character on said dial corresponding to the class of items located at a point between said spools.

3. In a device of the class described, a 70 casing, a pair of spools mounted in said casing, a strip of sheet material having one end wound about said spool, and the other end wound about the other spool, means to wind said strip from one spool to the other, 75 a list of items registered on said strip in alphabetical order, a dial mounted on said casing, letters registered on said dial, an indicating hand on said dial and means connected with said strip whereby the said hand is automatically moved to letters on said dial corresponding to the items on said strip as the same are positioned between said spools.

4. A suitable casing, a pair of spools mounted in said casing, a long strip of flexible material wound about said spools, names registered on said strip in alphabetical order, a dial mounted on said casing, index letters registered on said dial, an indicating hand on said dial, means to wind said strip from 80 one spool to another and means to move said hand to the index letters on said dial, indicating, at all times, the first letter of the names positioned between the two spools.

5. In a telephone directory, a suitable 95 casing, a pair of spools mounted in spaced relation in said casing, a strip of sheet material wound about said spools, a list of telephone users, with the number of each telephone registered on said strip in alphabetical order, a dial on said casing, alphabetical characters registered thereon corresponding to the first letters of each name, an indicating hand on said dial, a window in said casing and means to roll said strip from one spool 100 to another and automatic means connected therewith to move said indicating hand to the letter on said dial corresponding with the first letter of the names presented below said window.

6. In a device of the class described, a support, two parallel shafts rotatably mounted, in spaced relation, on said support, a spool fixed to each shaft, a motor mounted on said support, means connected with said motor 110 to cause the rotation of one of the spools when the motor is driven in a forward direction, said means adapted to cause the rotation of the other spool when the motor is driven in the reverse direction; a strip of sheet material wound about said spools, said strip adapted to be wound from one spool to the other by the operation of said motor, classified reading matter on said strip, electric conducting material secured to said 115 strip at points adjacent each class, a dial on said support, index characters on said dial, each of which indicate a class of said reading matter, a hand on said dial, an electro-magnet on said support, said electro-magnet 120 125

adapted to be connected to a source of electrical energy by said electric conducting material on said strip so as to cause the operation of said magnet as each class of 5 reading material passes between said spools and mechanism associated with said magnet to move said hand to the characters on said dial which indicate the class of reading matter located between said spools, substantially

10 as described.

7. In a device of the class described, a suitable support, two parallel shafts rotatably mounted, in spaced relation, on said support, a spool fixed on each shaft, a motor 15 mounted on said support, means connected with said motor to cause the rotation of one of the spools when the motor is driven in a

forward direction and means adapted to cause the rotation of the other spool when the motor is driven in the reverse direction, 20 a strip of sheet material wound about said spools, said strip adapted to be wound from one spool to another by the operation of said motor, classified reading matter on said strip, a dial on said support, index characters on said dial, each of which indicates a class of said reading matter, a hand on said dial and automatic means adapted to move said hand to the characters indicating the class of reading matter located between said 25 30 spools.

In testimony whereof I have hereunto set my hand.

GEORGE HENRY KEYSER.
